UNITED STATES PATENT OFFICE.

ALVIE V. KISER, OF WEST LIBERTY, OHIO.

DESIGN FOR A VEHICLE-TIRE.

SPECIFICATION forming part of Design No. 35,209, dated October 22, 1901.

Application filed September 1, 1899. Serial No. 729,269. Term of patent 14 years.

To all whom it may concern:

Be it known that I, ALVIE V. KISER, a citizen of the United States, residing at West Liberty, in the county of Logan and State of Ohio, have invented and produced a new and original Design for Vehicle-Tires, of which the following is a specification, reference being had to the accompanying drawings, forming a part thereof.

Figure 1 is a sectional view on the line xx of Fig. 2, and Fig. 2 a side elevation of one of the sides of the tire-channel.

As shown in the drawings, the leading or material feature of my design consists in the flaring channel or seat for the tire proper, with the exterior portion of said seat formed in a straight line extending from its outer periphery a short distance and connecting with a curved line which extends to the inner periphery of the tire-seat, such curved line curving outward, as illustrated in the drawings, such exterior portions of the flaring channel also connecting with the base portion of the channel, upon which is mounted a tire proper having a flat base with curved sides and rounded top.

The letter A represents the base of the tire-channel, and the letters B the sides thereof, such sides tapering upward and outward from the base, as shown at C, on the exterior. The 30 exteriors of these sides show a straight and curved face a and b , respectively. From the lower outer edge or corner of the sides the lower edges are inclined inward and meet the base A in such a manner that an obtuse 35 angle is formed between the base and each of the sides. The base of the tire c is straight; as shown at D, while the sides are formed by curved lines, as shown at E, such curved lines joining the arc of a circle of greater curvature than the sides, thus constituting curved sides with rounded edge.

Having thus fully described my invention, what I claim as new, and desire to secure by Letters Patent, is—

The design for a vehicle-tire, as herein shown and described.

ALVIE V. KISER.
